UNITED STATES PATENT OFFICE.

CHARLES J. TRAVERS, OF CHICAGO, ILLINOIS, ASSIGNOR TO ROYAL METAL MANUFACTURING COMPANY, OF CHICAGO, ILLINOIS, A CORPORATION OF ILLINOIS.

DESIGN FOR A WIRE CHAIR.

42,529.

Specification for Design.

Patented May 14, 1912.

Application filed January 3, 1911. Serial No. 600,671. Term of patent 7 years.

To all whom it may concern:

Be it known that I, CHARLES J. TRAVERS, a citizen of the United States, residing at Chicago, in the county of Cook and State of Illinois, have invented a new, original, and ornamental Design for Wire Chairs, of which the following is a specification, reference being had to the accompanying drawing, forming part thereof, and in which the

invention is illustrated by a perspective view of the chair.

I claim:

The ornamental design for a wire chair, as shown.

CHARLES J. TRAVERS.
